UNITED STATES PATENT OFFICE.

GEORGE W. FOSTER, OF WESTFIELD, MASSACHUSETTS.

YARN-CLEARER.

1,101,423.

Specification of Letters Patent.

Patented June 23, 1914.

Application filed November 21, 1912. Serial No. 732,652.

To all whom it may concern:

Be it known that I, GEORGE W. FOSTER, a citizen of the United States, residing at Westfield, in the county of Hampden and State of Massachusetts, have invented certain new and useful Improvements in Yarn-Clearers, of which the following is a specification.

My invention relates to yarn-clearers, slub detectors or the like, and consists of an improved device for cleaning specks, motes or other foreign matter from yarn or thread and for detecting slubs, bunches, knots or enlargements in the same and breaking them out.

My invention belongs to that class of devices in which the yarn is drawn through slots or across the edges of blades or plates and its object is to provide a more effective arrangement of the slots to insure complete contact of the yarn with the blades on all of its sides so that it will be thoroughly cleaned and the passage of all slubs or other enlargements will be obstructed.

My invention also embraces an improved adjusting device which provides for quick and accurate setting of the blades for different sizes of yarn.

The invention is fully explained in the following specification, illustrated by the accompanying drawings, in which:

Figure 1 is an enlarged plan view of my new device showing the preferred embodiment of the invention; Fig. 2, an end view of the same; Fig. 3, a plan view of another arrangement of the device with the yarn-guiding rods removed to illustrate the relation of the blades and slots; Fig. 4, an end view of the same; Fig. 5, a perspective view of one of the blade-members; Fig. 6, a plan view of the blank from which said member is formed; Fig. 7, a detail view of the yarn-guiding rod.

My invention consists essentially of two members supported in adjustable relation to each other with each member formed with spaced-apart blades having angularly disposed edges arranged to coöperate with the corresponding edges of similar blades on the other member to provide two crossing slots through which the yarn draws.

Referring first to Figs. 1 and 2, B designates a support or bracket formed with an arm b adapted to be secured by the set-screw c to any suitable cross-rod or bar C on the machine to which the device is applied.

The end of the bracket B is formed with a central, longitudinal slot b' and two parallel side slots b², b², see Fig. 2. The two blade-members D and D' are arranged to be held in the slot b', one member D' resting on top of the other one D. The members D and D' are practically identical in shape and contour and are preferably constructed of sheet-metal bent to the form shown. Referring to Fig. 6, which illustrates the "butterfly" blank from which the members are formed, this consists of the body portion d having two wings d' and d² extending laterally therefrom. The wing d' is formed with an edge d³ extending at an angle of approximately forty-five degrees to the edge of the body portion d and terminating in a point d⁴ where this edge joins the end of the straight edge d⁵. The wing d² extends in the straight edge d⁵ to a point d⁶ equidistant from the center of the body portion d with the point d⁴. From this point the edge d⁷ extends rearwardly at an acute angle to the edge d⁵ and at d⁸ rounds into the edge d⁹ which lies parallel to the outer edge d³ of the wing d', joining the body portion d at d¹⁰. To facilitate bending the stock the metal is cut out in a small circle at d¹⁰, and at d¹¹ the edge d³ joins the body portion d at right-angles to the latter's edge. In forming the blade-members the wings d' and d² are folded or bent upward from the body portion on the lines x, x, Fig. 6, and when completed extend perpendicularly thereto, as shown in Fig. 5. The member D' corresponds exactly to the member D in shape and form, except that in the preferred arrangement shown in Fig. 1 the body portion d continues rearwardly a slight distance farther from the wings and is bent down in a right-angled, tail-piece d¹². This extension d¹² is illustrated by the dotted lines in Figs. 5 and 6 and is designed to coöperate with the adjusting means to be later described. Both members D and D' are provided with slots d¹³, d¹³ extending longitudinally of their body portions, and adapted to receive the screws which secure them in place on the bracket B. The two members D, D' are assembled on the bracket B by reversing their positions and placing the body portion of the member D' on top of that of the member D so that it slides in between the wings or side blades d', d² of the latter. The side blades of the two members will thus be in alinement and their angular edges, being made to conform

one to another, will lie in parallel planes. That is to say, the edge d^3 of the member D will lie parallel and be adapted to contact with the adjacent edge d^9 of the member D' and the edge d^9 of the member D will be in similar juxtaposition to the edge d^3 of the member D', as shown most clearly in Fig. 3. It will also be noted that the arrangement of the contiguous edges on the opposite side 10 blades is such that they cross each other at approximately right-angles, this being an important feature of the invention. By sliding one of the members longitudinally in relation to the other the adjacent edges of the 15 blades may be brought together or separated to regulate the distance between them and thus adjust the width of the slots for different sizes of yarn. To provide for very accurate, minute adjustment I prefer to employ the arrangement illustrated in Figs. 1 20 and 2, which is similar to that of a micrometer caliper. The two members D and D' are held in place on the bracket B by the two screws E, E extending through the slots d^{13} , 25 d^{13} , and the lower member D is secured fixedly in place by means of two dowel-pins e , e driven through the holes d^{14} , d^{14} . By loosening the screws E, E the upper member D' can be slid longitudinally of the slot b' , 30 and to adjust this member I prefer to employ the means now described: Screwed in to the end of the bracket B is a screw F having a thread of relatively fine pitch or lead and a knurled head f formed with a circumferential groove f' . The tail-piece d^{12} of the sliding member D' reaches in to adapt its 35 end to engage the groove f' and by turning the screw this member can be adjusted in relation to the member D to vary the width 40 of the slots d^{15} , d^{16} between the edges of the side blades or wings d' , d' and d^2 , d^2 . The end of the screw head f is preferably marked with graduations, as illustrated in Fig. 2, 45 which are adapted to register with a pointer g , the latter forming part of a sheet-metal piece G secured to the extension d^{12} by the screw g' . The graduations on the screw head f may be numbered in sequence or marked to correspond to different sizes of 50 yarn for which the various adjustments are adapted. On either side of the members D and D' are provided guiding rods H, H which serve to direct the yarn y in its proper course through the slots d^{15} , d^{16} , that is, to 55 the point d^{17} where the two slots cross. These rods are preferably constructed of porcelain, glass or other vitreous material, and are provided with V-shaped grooves h at their centers, forming troughs in which 60 the yarn is centered. The rods H, H are preferably held in the slots b^2 , b^2 on the bracket B by means of sheet-metal clamps J, J bent around their ends and secured to the bracket B by the screws j , j . When the 65 grooves in the slots become worn or scored

from the abrasion of the thread or yarn the rods can be turned on their axes by loosening the clamps to present a new bearing surface for the yarn.

In the embodiment of my invention illustrated in Figs. 3 and 4, the micrometer adjustment is dispensed with, making the device more simple and easier to manufacture, but practically as efficient for ordinary use. As here shown, the members D and D' are not mounted in a slot in the bracket B, but are simply secured to the face b^3 , this construction being somewhat cheaper to manufacture. The member D is secured from movement by the dowel-pins e , e , and the member D' can be adjusted by loosening the screws E, E, and sliding it by hand. In adjusting the blade-members with this arrangement it is necessary to make use of a gage which is inserted between the edges of the blades to insure setting them at the proper distance apart according to the size of yarn for which the device is to be used. Where ordinary or coarse yarn is being cleaned the above arrangement is usually 90 satisfactory, but for very fine and even yarns the first described method of adjustment is preferable as it provides for greater accuracy and more minute adjustment, besides avoiding dependence on the judgment 95 of the operator.

The method of operation of my improved device is as follows: The binding screws E, E are first loosened and the adjusting screw F set with the pointer g indicating the number or size of the yarn being reeled or wound by the machine to which the device is attached. After the blade-members are thus adjusted to give the proper width of the slots the screws E, E are tightened 100 again to lock them in position. The yarn y is then drawn up across the lower rod H, through the V-shaped trough formed by the divergent edges d^7 and d^7 of the members D and D', and thence to the reeling 105 or winding devices. As the yarn is taken up by the machine to which it is being supplied the tension or draft of the winding operation will cause it to straighten out in its course and work down over the rounded points d^8 , d^8 until it seats in the groove h of the upper rod H. The two rods H, H are arranged with the bottom of their grooves in line with the crossing point d^{17} of the slots d^{15} and d^{16} and hence the yarn 110 will be directed and maintained in a straight course passing through the slots at this point. It will also be observed that as the rounded points of the two blades d^2 , d^2 overlap each other they will act as a guard to 115 prevent the yarn from whipping out of the slots as it balloons out from the supply cop during its uncoiling. Now, as the yarn draws through the two slots d^{15} , d^{16} it will 120 make a contact with the edges of the blades 125 130

on all of its four sides so that practically all of its surface is scraped and cleaned of the specks and motes which are liable to be left adhering during the process of manufacture or which may have been gathered in handling. When a slub, bunch or knot appears the tendency of the opposed edges of the first set of blades is to either flatten it out or obstruct its passage through the first slot d^1 , but should it be flattened sufficiently to pass through the first slot, it will be engaged by the second set of blades at right-angles to the flattened portion so that it becomes practically impossible for the enlargement to pass through both slots. That is to say, if the contact with the edges of the first set of blades only serves to flatten the yarn in the direction of the slot, the engagement with the second set being across this flattened portion is sure to obstruct its passage and if the slub is not cleared from the yarn then the latter will be held and broken, which is the result desired. In this way undue enlargements or imperfect places in the yarn are detected and may be broken out to the end that its quality will be improved and its value thereby enhanced. The yarn is thus thoroughly cleaned on all sides by contact with the angularly disposed edges of the two sets of blades, which also operate at what might be termed "cross purposes" to detect and break out any enlargements, slubs, bunches or knots.

From the above it will be seen that my improved device provides for a more thorough cleaning of the yarn than can be effected by a single slotted member and the novel cross-slot arrangement makes it practically impossible for a slub or knot to pass through the blades without detection. Furthermore, the blades may be adjusted with great accuracy and precision without the use of gages and without depending on the skill or judgment of the operator. The improved means for adjustment also provides against carelessness or negligence on the part of the operator, and the device when once set is locked against accidental displacement of the parts. My new device also provides for quick and easy threading, it being only necessary to draw the yarn across the guiding edges d^1 , d^2 of the blades and the tension on the yarn thereafter automatically draws it into the slots. It is also called to attention that the design of the two blade-members is particularly ingenious as providing that both may be punched out or struck-up from the same blank. This feature greatly cheapens the cost of manufacturing and also insures that when the members are assembled in reverse relation the contiguous edges of the yarn slots will lie in exact parallelism and be in proper alignment.

Various modifications might be made in

the form and structure of the parts of my new device without departing from the spirit or scope of the invention.

Therefore, without limiting myself to the exact arrangement shown, what I claim is:—

1. In a yarn-clearer, the combination of two members having pairs of spaced-apart blades with angularly disposed edges, the edges of one pair of blades adapted to co-operate with those of the other to form slots crossing each other at approximately right-angles, and arranged with the yarn drawing through the slots at their crossing points.

2. In a yarn-clearer, the combination of two members adjustable in relation to each other and each formed with a pair of separated blades having angularly disposed edges adapted to co-operate with corresponding edges of the other to provide slots extending across each other, and arranged with the yarn drawing through the slots at the crossing point.

3. In a yarn-clearer, the combination of spaced-apart blade-members arranged with their edges contiguous to form two slots crossing each other at substantially right-angles in different planes, and means to adjust said members in relation to each other to correspondingly regulate the width of both of the slots.

4. In a yarn-clearer, the combination of two members, each formed with a body portion having blades extending perpendicularly therefrom in different planes with the edges of the blades disposed at opposite angles to adapt those of one set of blades to lie contiguous to those of the other to form two crossing slots when the members are placed in reverse relation to each other.

5. In a yarn-clearer, the combination of two folded sheet-metal members having body portions with blades bent up from the sides thereof at right-angles thereto, and formed with edges disposed at opposite angles to adapt the edges of the blades of one member to co-operate with those of the other to form two slots crossing each other at substantially right-angles in different planes.

6. In a yarn-clearer, the combination of two members having blades formed with angularly disposed edges and arranged with the edges of the blades of one member contiguous to the opposite edges of the blades of the other member to provide slots crossing each other at substantially right-angles, and means to guide the yarn through the slots to direct it in a straight course through the crossing point of the slots.

7. In a yarn-clearer, the combination of two blade-members arranged in juxtaposition with the edges of the blades forming crossing slots, said blades shared with openings leading into the slots to provide guides for the yarn to direct it to the crossing

point, and means to adjust said members to regulate the width of both of the slots, each in conformity with the other.

8. In a yarn-clearer, the combination with two members, each formed with a pair of blades having angularly disposed edges, said members arranged with the edges of the blades coöperating to provide slots crossing each other at substantially right-angles and one blade on each member having a rounded point overlapping the corresponding point on the opposite blade of the other member in different planes to act as a guard to retain the yarn in position at the crossing point of the slots.

9. In a yarn-clearer, the combination with a bracket, of two blade-members mounted on said bracket with one member fixed and the other adapted to slide in relation thereto, the edges of the blades of said members being arranged to form crossing slots through which the yarn draws, and means to adjust the sliding member in relation to the fixed member to simultaneously regulate the width of both of the slots.

10. In a yarn-clearer, the combination with a bracket, of two blade-members mounted thereon and arranged with the edges of the blades coöperating to provide slots crossing each other in different planes at substantially right-angles, and a screw engaging one of the members to adjust it in relation to the other member, to simultaneously regulate the width of both of the slots.

11. In a yarn-clearer, the combination with a bracket, of two members mounted thereon and provided with coöperating blades having their edges forming slots crossing each other at substantially right-angles in different planes, a screw engaging one of the members to adjust it in relation to the other member to simultaneously regulate the width of both slots, said screw provided with graduations, and an index pointer adapted to register with the graduations on the screw to indicate the adjustments made thereby.

12. In a yarn-clearer, the combination with a bracket, of two blade-members, one fixed and the other slideable on the bracket, said members provided with coöperating blades arranged with their edges forming slots crossing each other at substantially right-angles in different planes, a screw in said bracket formed with a head having a circumferential groove, and an extension on the slideable member adapted to engage said groove to cause movement of said member to simultaneously adjust the width of both slots when the screw is turned.

In testimony whereof I affix my signature in presence of two witnesses.

GEORGE W. FOSTER.
